Primary Examiner — Karen E Eldridge Powers(74) *Attorney, Agent, or Firm* — Lawrence Cruz, Esq.; Joseph W. Schmidt, Esq.(57) **CLAIM**

The ornamental design(s) for a heated hair paddle, as shown and described.

DESCRIPTION

FIG. 1 is a perspective view of the heated hair paddle in accordance with the principles of the present disclosure

FIG. 2 is a top plan view of the heated hair paddle;

FIG. 3 is a first side elevation view of the heated hair paddle;

FIG. 4 is a second side elevation view of the heated hair paddle;

FIG. 5 is a bottom plan view of the heated hair paddle;

FIG. 6 is a rear elevation view of the heated hair paddle; and,

FIG. 7 is a front elevation view of the heated hair paddle.

Features shown in broken lines illustrate environmental structure and form no part of the claimed design.
